UNITED STATES PATENT OFFICE.

SIMON E. DAVIS, OF SAN FRANCISCO, CALIFORNIA, ASSIGNOR TO NEUSTADTER BROTHERS, OF SAN FRANCISCO, CALIFORNIA, A CORPORATION OF CALIFORNIA.

REINFORCED POCKET.

Application filed March 23, 1927. Serial No. 177,603.

This invention relates to a reenforced pocket structure and especially to a pocket of the type used by carpenters and mechanics for carrying nails, etc.

5 It is common practice at the present time to attach a pocket to the bib or apron of carpenter's overalls which serves the purpose of a receptacle for nails, etc. It is also common practice to divide the pocket into a number 10 of compartments for the reception of nails of different sizes and it is furthermore common practice to reenforce the pockets to prevent puncturing of the fabric and to prevent too rapid wear.

15 A reenforced pocket of this character, briefly, consists of a section of fabric forming the pocket proper. This fabric is usually referred to as the lining. The lining material is covered by an exterior section of fabric 20 which is sewed thereto and this is referred to as the reenforcing fabric.

The inner fabric or lining usually wears through fairly rapidly and the nails then begin to work in between the lining and the 25 reenforcing fabric where they become lodged. Nails and other objects which become lodged in this manner are difficult to remove and are a source of nuisance and inconvenience.

30 The object of the present invention is to generally improve and simplify the construction and operation of pockets of this character and particularly to attach the reenforcing fabric in such a manner that even though the lining fabric becomes punctured or worn 35 through, neither nails nor other objects will be able to work through or become lodged between the lining and reenforcing fabric.

The reenforced pocket is shown by way of 40 illustration in the accompanying drawings, in which:

Fig. 1 is a front view of the upper portion of a carpenter's overalls, said view showing the attachment of the reenforced pocket,

45 Fig. 2 is an enlarged cross section of the reenforced pocket taken on line II-II, Fig. 1.

For the purpose of illustration an ordinary carpenter's overalls is shown in which 50 A indicates the leg portions, B the upper or apron portion and C the straps or suspenders whereby the bib is supported with relation to the shoulders.

The pocket structure forming the subject 55 matter of the present application is generally indicated at D and is in this instance

shown as two series of pockets, 2 and 3, each of which may be divided into a number of compartments such as indicated at 4, 5, 6 and 7 to permit segregation and separation of nails of different sizes. The pockets are 60 sewed or otherwise attached to the apron along the line indicated at 8 and while two sets of pockets are here illustrated, the description of one pocket will suffice as they are both identical in construction. 65

The pocket is constructed as follows:

A section of fabric such as canvas or the like is folded longitudinally as at 9 to form a back section 10 and a front section 11. The ends of the fabric are then sewed together at 70 the ends as indicated at 12 and an elongated pocket is thus formed in which the folded portion 9 forms the bottom. If it is desired to divide the pocket into a number of compartments, vertical stitching is employed as 75 indicated at 13 and any number of compartments may in this manner be obtained. The bottom portion of a pocket of this character is usually subjected to the greatest wear and the only portion that requires reenforcing 80 is accordingly the lower portion. The reenforcing material may be any suitable fabric but usually a heavier grade of canvas or the like such as indicated at 15. This material is folded longitudinally upon itself to cover 85 the rear section 10 and the front section 11. The front section of the reenforcing material is indicated at 15 and the rear section is shown at 15a. The reenforcing material under ordinary conditions is usually stitched to 90 the pocket along the upper edges 16, both at the front and the rear and around the ends as indicated at 17. This manner of attaching the reenforcing material is not satisfactory as the inner fabric or lining material 95 soon wears through and the nails or other objects carried will then work in between the lining and the reenforcing material and will then become lodged as previously stated.

To obviate this objectionable feature, the 100 lining material is, in this instance, sewed horizontally at a number of points as indicated by the lines 18 and the reenforcing material and the diagonal stitching shown by the lines 19 and 20 producing a maze of 105 intersecting lines of sewing, both horizontally and vertically and the stitching is so close as to so unite the lining material and the reenforcing fabric that no space is left into which nails or other objects can work. 110

In fact, it is necessary that the lining material and the reenforcing fabric become completely worn through before nails or other objects can escape and if they then do work through, they will fall to the ground.

While the reenforcing material is here shown as being attached to nail pockets and the like it is obvious that it may be attached to ordinary garment pockets and that it may have other uses.

While certain features of the present invention are more or less specifically described and indicated, I wish it understood that various changes may be resorted to within the scope of the appended claim; similarly, that the materials and finish of the several parts employed may be such as the manufacturer may dictate or varying conditions or uses may demand.

Having thus described my invention, what I claim and desire to secure by Letters Patent is:

A pocket structure for carrying nails and

the like formed of a piece of material folded longitudinally upon itself to form sides and bottom of a pocket, the ends of the sides being stitched to complete the pocket, a reenforcing fabric covering for said pocket comprising a piece of material folded longitudinally around the bottom of the pocket and partially over the front and rear sides of the pocket in contact therewith, said reenforcing fabric being stitched about its boundary to the sides and ends of the pocket, and a plurality of closely spaced lines of stitching some of which extend horizontally and others at opposite oblique angles thereto throughout the portion of the reenforcing fabric covering the front and rear walls of the pocket intimately uniting the reenforcing fabric to the sides and bottom of the pocket at a plurality of closely adjacent points whereby a nail or the like is prevented from lodging between the reenforcing fabric and pocket.
